DESIGN FOR A HANDLE FOR AN ELECTRIC
LAUNDERING IRON

Percy William Davis, Broadwell, Oldbury, England, assignor to Simplex Electric Company Limited, Broadwell, Oldbury, England

Application October 3, 1939, Serial No. 87,492
In Great Britain June 22, 1939

Term of patent 3½ years

To all whom it may concern:

Be it known that I, Percy William Davis, a subject of the King of Great Britain and residing at Broadwell Road, Broadwell, Oldbury, in the county of Worcester, England, have invented a new, original, and ornamental Design for a Handle for an Electric Laundering Iron, of which the following is a specification, reference being had to the accompanying drawing forming part hereof and in which,

Figure 1 is a side perspective view of a handle

for an electric laundering iron showing my new design.

Figure 2 is a side perspective view thereof from a different angle.

Figure 3 is a side elevation of a view taken from the opposite side of said handle.

Figure 4 is a top plan view of said handle.

I claim:

The ornamental design for a handle for an electric laundering iron substantially as shown.

PERCY WILLIAM DAVIS.
